UNITED STATES PATENT OFFICE.

CHARLES SCHOFIELD, OF NEWCASTLE-UPON-TYNE, ENGLAND.

HOLDER-ON.

972,257.

Specification of Letters Patent. Patented Oct. 11, 1910.

Application filed January 21, 1910. Serial No. 539,239.

To all whom it may concern:

Be it known that I, CHARLES SCHOFIELD, a subject of the King of the United Kingdom of Great Britain and Ireland, residing at Milburn House, Newcastle-upon-Tyne, in the county of Northumberland, in that part of the United Kingdom called England, have invented a new and useful Holder-On, of which the following is a specification.

10 This invention consists in an improved holder-on for use in connection with pneumatic riveters and in carrying it into effect I proceed substantially as follows making reference to the accompanying drawings where-
15 in—

Figure 1 is a part sectional side view of the complete implement and Figs. 2, 3, 4 and 5 details of parts to be hereinafter mentioned.

20 I provide a casing *a* of suitable dimensions and closed at one end by a cap *b*, the opposite end being formed as at *c* to accommodate a snap *d* free to slide therein. Within the casing *a* is a piston *e* between the inner end of which and a cap *f* is a spiral spring *g*, the cap *f* being free to slide longitudinally to a limited extent. The movement of *f* is determined by slots *h* in the casing, in which slots are free to slide screws *i* carried by the cap *f*, the outer face of the cap being somewhat recessed as at *j*.

Free to slide through the cap *b* is the stem *k* of a socket *l*, in which stem is an adjustable screw *m*, and between the cap *b* and a
35 shoulder *n* on the said stem is a spiral

spring *o*. The inner end of the socket *l* is formed to receive the shank *p* of a fork *q* each arm of which is cam-slotted as at *r* to receive a pin *s* outstanding on each side of the head *t* of the cam lever *u*, to accommodate which lever head *t* and fork *q*, slots are provided at *v* and *w* in the casing *a*.
40

What I claim as my invention and desire to secure by Letters Patent is:—

In a holder-on for use with a pneumatic riveter, the combination of a slotted outer casing; a snap at one end of the casing; a piston within the casing; a spiral spring behind the said piston; a slidable cap to receive one end of the spiral spring; means for 45 limiting the movement of the said slidable cap; a cam lever having a pin outstanding on each side; a fork, cam-slotted to receive the ends of the said pin, and having a stem at one end; a spring controlled socket adapt- 50 ed at one end to receive the said stem and at the other end having a shank provided with an adjustable screw, and a cap at this end of the casing through which cap the said shank passes and against which acts one end 55 of the spring controlling the socket, substan- 60 tially as hereinbefore described.

In testimony whereof I have signed my name to this specification in the presence of two subscribing witnesses.

CHARLES SCHOFIELD.
